UNITED STATES PATENT OFFICE.

LUCAS M. KUEHN, OF WABASHA, MINNESOTA.

ELEVATOR.

SPECIFICATION forming part of Letters Patent No. 487,576, dated December 6, 1892.

Application filed May 10, 1892. Serial No. 432,430. (No model.)

To all whom it may concern:

Be it known that I, LUCAS M. KUEHN, of Wabasha, in the county of Wabasha and State of Minnesota, have invented a new and Improved Elevator, of which the following is a full, clear, and exact description.

The object of the invention is to provide a new and improved elevator which is simple and durable in construction and is more especially designed for use on large ice-boxes and other receptacles for conveniently elevating and depositing blocks of ice or other articles in the receptacles.

The invention consists of a frame adapted to be raised and lowered and provided with a platform mounted to swing on the frame and adapted to be automatically tripped to move into an inclined position, so as to automatically deliver the elevated article into the desired place.

The invention also consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is an end elevation of the improvement with parts in section. Fig. 2 is a sectional side elevation of the same. Fig. 3 is a side elevation of the platform in an inclined position; and Fig. 4 is a sectional plan view of the platform-frame and guide-post, the latter being shown in section.

The improved elevator is mounted on a post A, erected in the immediate neighborhood of the ice-box or other receptacle on which the elevator is to be used. On this post A is mounted to slide vertically a frame B, provided with a front plate B', from the sides of which extend the arms B², supporting at their outer ends a friction-roller B³, engaging the back of the post A, while the arms B² engage the sides thereof and the plate B' the front of the post, so that the frame travels easily up and down the post. The front plate B' is, in addition, provided with flanges B⁴, fitting on the sides of the post A. (See dotted lines in Fig. 4.) From the plate B' extends a pin C, engaging a bearing D', formed on the

under side of a platform D, mounted to turn on the said pin, so as to swing from a horizontal position, as shown in Fig. 2, into an inclined position. (Illustrated in Fig. 3.) This platform 55 D is provided with a front side D² and a rear side D³, connected with each other at one end by a back D⁴, while the other end is formed by a gate or chute E, hinged to the front end of the platform, as shown in Figs. 2 and 3. 60 On the rear side D³ is formed a segmental slot D⁵, concentric with the pin C, and this slot is engaged by a screw or bolt F, held in the post A. The slot D⁵, with the screw or bolt F, limits the swinging or tilting motion of 65 the platform D. At the rear side D³, next to the chute E, is formed a lug G, adapted to be engaged by a fixed arm H, projecting from the receptacle, into which the article is to be delivered, or from a separate bracket, as the case 70 may require. The lugs G and H constitute a tripping device for the platform D, so that the latter is moved automatically into an inclined position, as hereinafter more fully described. 75

The upper end of the plate B' of the frame B is connected with a rope I, extending upward and passing over a pulley J, journaled in a recess in the upper end of the post A. The rope I then extends downward and winds 80 on the hoisting-drum K, the shaft K' of which is journaled in a bracket A', attached to the rear side of the post A. On the shaft K' is secured a gear-wheel L, in mesh with a pinion M, mounted to rotate loosely on a shaft 85 O, secured in the bracket A' above the shaft K'. On this shaft O is fulcrumed loosely a lever P, carrying a spring-pressed pawl Q, engaging a ratchet-wheel R, secured on the front face of the pinion M. The outer end of the 90 pawl Q is in close proximity to the handle of the lever P, so that the pawl can be conveniently disengaged from the ratchet-wheel R, for the purpose hereinafter more fully described. The lever P can be locked in place 95 when the platform is raised by means of a chain S, attached at one end to the bracket A' and formed at its other end with a ring adapted to be hooked over the handle of the lever P. 100

The operation is as follows: When the platform D and the frame B are in a lower-

most position at the bottom of the post A, then the block of ice or other article can be conveniently placed on the platform, the latter then extending horizontally. When the 5 block of ice has been deposited, the chute E is swung upward against the block of ice, (see Fig. 2,) and then the operator takes hold of the lever P and turns the same, so that the pawl Q, in engagement with the ratchet- 10 wheel R, turns the latter on the fixed shaft O, and as the said ratchet is attached to the pinion M the latter rotates with it and imparts a rotary motion to the gear-wheel L, secured on the shaft K', carrying the drum K. The 15 latter is thus rotated and winds up the rope I, whereby the frame B, the platform D, and the article supported thereon are elevated, the frame B traveling up on the post A as a guideway. When the lug G strikes against 20 the lug H on the upward movement of the platform, then the latter is tilted into the position shown in Fig. 3, the article supported on the platform then sliding down the same, thereby swinging the chute E outward and 25 into the opening of the ice-box or other receptacle, so that the block of ice or other article is directly guided into the ice-box through the open door of the same. As soon as the block of ice has been deposited in the ice-box 30 the operator presses on the free end of the pawl Q, so as to disengage the same from the ratchet-wheel R, whereby the frame B and the platform held thereon cause a downward sliding of the same on the guide-post A, 35 thereby unwinding the rope I from the drum K. The platform thus moves into a lowermost position to receive another block of ice, which is then elevated and deposited in the receptacle in the manner above described. 40 As shown in Fig. 2, the bearing D' is somewhat to one side of the middle of the platform D, so that the latter when empty always returns to a normal horizontal position. (Shown in Fig. 2.) 45 When the frame B and platform D are not in use, they are held in an elevated position at the upper end of the post A, the lever P then being locked in place by the chain S, as shown in Fig. 1, to prevent the automatic de- 50 scent of the frame and platform. By the use of the chain S the frame and platform, with the articles supported thereon, may be held in any desired position.

Having thus described my invention, I 55 claim as new and desire to secure by Letters Patent—

1. The combination, with a vertical post, of a vertically-sliding frame having arms embracing the post and provided with a horizontal pin projecting at right angles from its outer face, a platform pivoting upon the said

pin to swing vertically, and means for automatically tilting the platform, substantially as set forth.

2. The combination, with a frame constructed to slide vertically and a pin projecting at right angles from the outer face of said frame, of a tilting platform pivoting at one side of its center of gravity upon said pin and normally lying in and returning to a horizontal position after tilting, substantially as set forth. 65

3. The combination, with a vertically-sliding frame provided with a pin projecting at right angles from its outer face, of a tilting platform mounted at one side of its center of gravity upon said pin and normally lying in a horizontal position and a pin-and-slot connection between the platform and the frame to limit the tilting movement of the latter, 70 substantially as set forth. 75

4. The combination, with the vertically-sliding frame comprising plate B', arms B² B², and roller B³, of the horizontal tilting platform on the front face of the plate and having 85 a flange D³, provided with a slot D⁵, a pin passed through the slot into plate B', and the chute E, hinged at its lower edge to the dumping edge of said platform, substantially as set forth. 90

5. An elevator comprising a vertical post, a winding-drum at the lower end thereof, gearing for operating the drum, a lever having a pawl-and-ratchet connection with the said gearing to operate it, a guide-pulley at the 95 upper end of the post, a frame sliding upon the post and having a pin projecting from its outer face, a normally-horizontal tilting platform mounted on said pin and having a lug and a downward-swinging chute at its dumping edge and a lug in the upward path of the first lug to tilt the platform, and a rope extending from the drum over the guide-pulley and down to the sliding frame, substantially as set forth. 100

6. The combination, with the vertically-sliding plate comprising a plate B', provided with parallel arms B², vertical flanges B⁴, roller B³ between the rear ends of arms B², and the pin C, projecting at right angles from the outer face of plate B', of the normally-horizontal platform D, mounted on the pin and having a rear end flange D⁴, outer side flange D², and inner side flange D³, having a slot D⁵, a pin extending through the slot into the plate B', 110 trip-lug G, and the inward inclined chute E, hinged at its lower edge to the dumping end of the platform, substantially as set forth. 115
